HAIRPIN REMOVER

Walter Linden and Elsie Van Brun, Bronx, N. Y.

Application January 27, 1937, Serial No. 122,676

1 Claim. (Cl. 175—367)

This invention appertains to new and useful improvements in beauty shop appliances and more particularly to a convenient device for extracting hair pins from the hair of patrons.

5 The principal object of the present invention is to provide a magnet device which can be applied to the hair of patrons in beauty shops and elsewhere for quickly and conveniently removing all hair pins.

10 Another important object of the invention is to provide a device of the character stated which will not be susceptible to the ready development of defects.

These and various other important objects and 15 advantages of the invention will become apparent to the reader of the following specification.

In the drawings:—

Figure 1 represents a perspective view of the apparatus.

20 Figure 2 is a vertical sectional view through the battery case.

Figure 3 is a horizontal sectional view through the battery case.

25 Figure 4 is a longitudinal sectional view through the magnetic unit.

Figure 5 is a cross sectional view on the line 5—5 of Figure 4.

Referring to the drawings wherein like numerals designate like parts, it can be seen in Figure 30 1, that numeral 5 generally refers to the battery case, while numeral 6 generally refers to the magnetic unit. The case 5 consists of the box-like receptacle 7 in which a plurality of dry cells 8 can be disposed and these are connected as at 9 35 in series, the terminal wires being connected to the switch 10 located in the top 11 of the case. This top 11 is provided with a suitable handle 12 and is provided with an opening through which the conductor cord 13 is disposed. The cord 13, 40 when the appliance is not in use can be wrapped around the holding hook 14 and at the outer end of this cord 13 is the magnetic unit 6. When the magnetic unit is not in use, the same can be supported by the spring clip 15 located on the side of 45 the receptacle 7.

As is clearly shown in Figures 4 and 5, this magnetic unit 6 consists of the cylindrical case 16 of insulation having one end provided with an opening therein, the edge portion of which is 50 beveled as at 17. Against this beveled edge portion fits the beveled edge portion of the mag-

netizable plate 18, the core 19 projecting therefrom, extending through the magnetic coil 20. This coil 20 has a separator 21 interposed between one end thereof and the magnetizable plate 18, and has the insulating plate 22 at its 5 opposite end. The conductors of the cord 13 extend through the cap 23 of the case 16, this cap 23 being provided with the internally threaded apron-like portion 24 for engagement over the externally threaded adjacent end portion of the 10 case 16 and is disposed in clamping engagement with the dielectric plate 22 so that the magnetic coil assembly is firmly held in the case 16. Suitable ventilating openings 25 are provided in the case 16. 15

Obviously, when the switch 10 is operated to connect the coil 20 with the batteries 8, the magnet becomes energized and any hair pins within the magnetic area of the magnetizable plate 18 will be attracted to the plate. In this manner 20 hair pins of paramagnetic material can be easily extracted from the hair without any inconvenience to the operator.

While the foregoing specification sets forth the invention in specific terms, it is to be understood 25 that numerous changes in the shape, size and materials may be resorted to without departing from the spirit and scope of the invention as claimed hereinafter.

What is claimed is:—

30 An electro-magnetic unit comprising a case of insulation open at its opposite ends and provided with an inwardly disposed circumferential portion at one end having an inwardly flaring bevel, a core structure provided with a pick-up plate 35 at one end thereof, said pick-up plate being provided with a bevelled edge portion for seating engagement against the bevelled surface of the inwardly disposed end portion of the case, a coil on the core, said core extending longitudinally 40 in the case, a plate of insulation disposed against the other end of the core and being adapted to fit snugly within the adjacent end portion of the case, the last mentioned end portion of the case being provided with external threads, a cap having 45 a laterally disposed portion for engagement against the plate of insulation and an internally threaded skirt for engagement with the threads of the last mentioned end of the case.
